DESIGN FOR A HANDBAG OR THE LIKE

William D. Phelps, New York, N. Y., assignor to Mark Cross Company, New York, N. Y., a corporation of New York

Application May 31, 1943, Serial No. 110,335

Term of patent 14 years

To all whom it may concern:

Be it known that I, William D. Phelps, a citizen of the United States, residing at New York city, county and State of New York, have invented a new, original, and ornamental Design for a Handbag, or the like, of which the following is a specification, reference being had to the accompanying drawings, forming part thereof.

Fig. 1 is a perspective view of a handbag showing my new design in open position;

Fig. 2 is a bottom plan view thereof; and
Fig. 3 is a perspective view thereof in closed position.

I claim:

The ornamental design for a handbag or the like, substantially as shown.

WILLIAM D. PHELPS.
